United States Patent Office

Des. 210,363
Patented Mar. 5, 1968

210,363

VEHICLE SEAT

Chester J. Barecki, Grand Rapids, Mich., assignor to
American Seating Company, Grand Rapids, Mich.,
a corporation of Delaware

Filed Nov. 25, 1966, Ser. No. 4,809

Term of patent 14 years

(Cl. D15—8)

FIG. 1

FIG. 2

FIGURE 1 is a perspective view from the front of a transportation seat showing my new design; and

FIGURE 2 is a perspective view of the same taken from the rear of the transportation seat.

The design is characterized by the paired inwardly recessed back portions extending below the head portion of the back and downwardly to the top of the seat members as shown in FIGURE 2.

I claim:

The ornamental design for a vehicle seat, as shown and described,
